UNITED STATES PATENT OFFICE.

VINCENT W. WILSON, OF PAWTUCKET, RHODE ISLAND, ASSIGNOR TO THE
R. BLISS MANUFACTURING COMPANY, OF SAME PLACE.

TOY HOUSE.

SPECIFICATION forming part of Letters Patent No. 535,779, dated March 12, 1895.

Application filed November 13, 1894. Serial No. 528,684. (No model.)

To all whom it may concern:

Be it known that I, VINCENT W. WILSON, a citizen of the United States, residing at Pawtucket, in the county of Providence and State 5 of Rhode Island, have invented a new and useful Improvement in Toy Houses, of which the following is a specification.

My invention consists in the improved construction and arrangement of parts as hereininafter fully set forth.

Figure 1, represents a front elevation of a toy house embodying my invention. Fig. 2, represents a central transverse section. Fig. 3, represents a central longitudinal section.

Fig. 4, represents a plan view of the board which forms the base of the structure. Fig. 5, represents the folding side wall of the structure in its outspread condition. Fig. 6, represents the perforated folding roof in its outspread condition. Fig. 7, represents the front elevation of a toy house embodying my invention, showing a modification having a double, instead of a single roof. Fig. 8, represents a transverse vertical section taken in the line 25 8, 8, of Fig. 7. Fig. 9, represents a central longitudinal section. Fig. 10, represents the folding side walls in their outspread condition. Fig. 11, represents the perforated roof in its outspread condition. Fig. 12, represents a plan view of the board which forms the base of the structure. Figs. 13 and 14, represent enlarged detail sections of the fibrous material of the side walls showing the mode of forming the corner joints.

In the drawings, Figs. 1 to 6, A represents the board which forms the base of the structure, the said board being provided with the saw-cuts $a a', a' a'', a^2 a^2$, which are adapted to receive the downwardly projecting bottom 35 portions, $b b', b' b'', b^2 b^2$ of the folding side walls B, of the structure, so as to hold the said walls in their proper upright position, as shown in Fig. 1.

The side walls B are made of stiff fibrous material, with a lithograph print c pasted upon its outer side, and upon the attachment of the lithograph print c the cuts $d d$, are made, cutting through the print and nearly through the supporting material, so that the said material 45 may be folded at the lines of the cut $d d$, to

form the corners of the side walls as shown in Figs. 13 and 14, and also to form a close package for shipment.

The removable posts C C, are adapted to loosely enter the holes $e e$, made in the board A, and serve to support the projecting portion of the roof D, which is formed of the same or a similar material to that of the side walls B, and similarly cut nearly through for folding upon the lines g, g, g , to the angular form 55 shown in edge view in Fig. 1, the said roof being held upon the posts C, C, and upon the gable-end pieces G G, by means of the removable pins h, h .

The gable-end pieces G, G, are provided at 65 their lower edges with the grooves r , adapted to receive the upper edge of the front and rear portions of the side walls B, the side walls being so formed as to leave an opening H at one side for the ready insertion of toy articles in 70 the house.

The roof D is provided with the oppositely directed triangular perforations i, i , and with the elongated perforation j , which is adapted to receive the chimney E.

The gable F is made of a sheet of similar material to that of the roof D, secured to the triangular gable ends k, k , the said gable being preferably made to extend from side to side of the roof, through the said perforations 80 i, i , thus tending to hold the roof D in position.

The chimney E is provided with the dowel pin m , which enters the hole n at the central portion of the top of the gable F.

A toy house of this construction is very 85 readily taken down for transportation and set up for use, the employment of the gable extending through the perforations made in the roof to receive the same, being the main feature of my improvement.

A modification of my invention is shown in Figs. 7 to 12, which shows a similarly built toy house, with a double roof, the said roof being provided with the triangular perforations i, i , and the diamond shaped perforations i' , adapted to receive the continuous gable F, as shown in Fig. 1, and in this case the chimney E may be inserted into a perforation o , in the top of the gable F, and extend downward to a lengthwise strip p , being 90 95 100

loosely secured thereto by means of the dowel pin *q*. The board *A* which forms the base of the house is provided at its forward corners with the saw-cuts *a a*, as in Fig. 4, to receive 5 the forward corners *b b*, of the side walls *B*.

I claim as my invention—

1. In a toy-house, the combination of the folding roof provided with the perforations at its opposite sides, with a gable adapted to extend through the perforations, substantially 10 as described.
2. In a toy-house, the combination of the

base-board, and the folding side-walls providing an opening for access to the interior, with the gable-end pieces grooved to receive the upper edges of the side-walls, the roof provided with perforations upon its opposite sides, and the gable adapted to extend through the perforations, substantially as described. 15

VINCENT W. WILSON.
